UNITED STATES PATENT OFFICE

150,815

DESIGN FOR A BOTTLE CARRIER

Robert G. Stigler, Dayton, Ohio, assignor to
 Standard Molding Corporation, Dayton, Ohio,
 a corporation of Ohio

Application July 26, 1946, Serial No. 131,979

Term of patent 14 years

(CL. D58—4)

To all whom it may concern:

Be it known that I, Robert G. Stigler, a citizen of the United States of America, residing at Dayton, in the county of Montgomery and State of Ohio, have invented a new, original, and ornamental Design for Bottle Carrier, of which the following is a specification, reference being had to the accompanying drawing, forming a part thereof.

Fig. 1 is perspective view from one side of a bottle carrier embodying my new design, showing the carrying handle in lowered position;

Fig. 2 is a top plan view of the same; and

Fig. 3 is an end elevational view showing the carrier with the carrying handle in raised position.

I claim:

The ornamental design for a bottle carrier, substantially as shown and described.

ROBERT G. STIGLER.
